C. F. MATTINGLY

VALVE

Filed Dec. 14, 1921

By *Watson E. Coleman*
Attorney

UNITED STATES PATENT OFFICE.

CHARLES F. MATTINGLY, OF ST. LOUIS, MISSOURI, ASSIGNEE TO MATTINGLY AUTOMATIC VALVE CO., OF ST. LOUIS, MISSOURI, A CORPORATION OF MISSOURI.

VALVE.

Application filed December 14, 1921. Serial No. 522,426.

To all whom it may concern:

Be it known that I, CHARLES F. MATTINGLY, a citizen of the United States, residing at St. Louis, in the State of Missouri, have invented certain new and useful Improvement in Valves, of which the following is a specification, reference being had to the accompanying drawings.

This invention relates to certain improvements in valves and has relation more particularly to a device of this general character especially designed and adapted for use in connection with a water gage, and it is an object of the invention to provide 10 a novel and improved device of this general character which can only be operated in two positions, namely, either wide open or closed.

Another object of the invention is to provide 20 a novel and improved device of this general character which cannot be adjusted in a manner which will create a false registration of the water within a gage glass.

It is also an object of the invention to 25 provide a novel and improved device of this general character wherein the valve is maintained open under proper pressure at opposite sides thereof, together with means whereby the valve is automatically caused 30 to close upon reduction of such pressure at one side of the valve.

The invention consists in the details of 35 construction and in the combination and arrangement of the several parts of my improved valve whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a valve constructed in accordance with an embodiment of my invention; and

50 Figure 2 is a view partly in section and partly in elevation of the structure as herein disclosed, said view being at a quarter turn relative to Figure 1.

As herein disclosed, my improved valve 55 comprises a casing C having its outer end

closed by a removable plug 1 which, when removed, facilitates the proper mounting of the gage glass G, said glass being readily insertible through the casing C. Engaged with the inner portion of the casing C is 60 a sleeve or nut 2 which serves to maintain the glass G in working position.

The casing C has a portion 3 outwardly offset and extending laterally from said offset portion 3 and in communication with the chamber X afforded thereby is a tubular extension 4 provided with an internal valve seat 5 adjacent its inner end and having its outer end closed by the removable plug 6. In communication with the bore 70 of the extension 4 and extending laterally therefrom and in a general direction toward the casing C is a nipple 7 adapted for communication with a boiler and preferably through a connection afforded by an adapter 75 8. The wall of the extension 4 remote from the nipple 7 and at a point aligned with the bore thereof is provided with an opening 9 normally closed by a removable plug 10, said plug 10 being easily removed to facilitate the cleansing of the interior of the casing C and the extension 4.

Communicating with the interior of the chamber X and in threaded engagement with a side wall of the offset portion 3 of 85 the casing C is a bushing 11, the inner portion of the bore of said bushing being formed to provide a valve seat 12. Slidably disposed through the bushing 11 is a stem 14 provided at its inserted end portion with a valve 15 for coaction with the valve seat 12. The stem 14 is of a diameter less than the diameter of the bore of the bushing 11 so that, when the valve 15 is in open position, steam and water may flow outwardly 95 through said sleeve.

The stem 14 is of such a length to extend at all times outwardly beyond the exterior end of the bushing 11 with said outer end of the stem bifurcated. Disposed through 100 the kerf 16 of said bifurcated extremity and pivotally engaged with the stem 14 through the medium of the pin 17 is an operating lever 18. This lever 18 extends above and below the stem 14 and has its lower end portion extending within the kerf 19 provided in the bifurcated outer end of the arm 20 extending outwardly from the offset portion 3 of the casing C and in the same 105 general direction as the bushing 11. The 110

lower end portion of the lever 18 is pivotally engaged with said arm 20 through the instrumentality of the pin 21.

The lever 18 provides means whereby the valve 12 may be manually moved into either opened or closed position. The lever 18 also serves to indicate the position of the valve 15 as said lever 18 is inclined in a position away from the casing when the valve 15 is closed and the main valve M (to be hereinafter referred to) is opened and leaning toward the casing when the valve 15 is opened and said main valve M closed.

The stem 14 has its inner or inserted end portion provided with an extension 14' having laterally extending therefrom a pin 22 which extends within the kerf 23 of the bifurcated upper end portion of a lever or link 24. This connection between the extension 14' and the lever or link 24 may be readily disengaged when the bushing 11 is removed for any purpose, such as the grinding of the valve 15 on its seat.

The central portion of the lever or link 24 is loosely mounted upon a pin 25 supported by and bridging the space between the outer wall of the offset portion 1 and a bar extending transversely across the inner or open end of the chamber X and integrally formed or otherwise supported by the side walls of said chamber.

The main valve M hereinbefore referred to is positioned within the extension 4 and contacts with the valve seat 5 therein. The valve M is mounted upon a stem 26 which extends inwardly of the chamber X and is provided with a head 27 pivotally connected, as at 28, with the lower end portion of the lever or link 24.

In practice, it is to be understood that the valve mechanism hereinbefore described is in communication with the boiler above the water line and is a duplicate of the casting of a second mechanism in communication with the boiler below the water line.

In operation, it is to be understood that when the lever 18 of each of the valve mechanisms is in a position inclined toward the adjacent casing, the associated main valve M is closed and the coacting valve 15 opened. By pulling outwardly upon each of the levers 18, the positions of the valves M and 15 are reversed, thus effecting the desired communication between the boiler and the glass G. The connection afforded between the valves M and 15 through the instrumentality of the lever or link 24 causes the valves M and 15 to move in unison but in reverse directions so that, when one of said valves M or 15 is opened, the other is closed. When the desired communication is effected with the boiler, the pressure is equalized at opposite sides of each of the valves M and the resultant pressure within the glass G and the casing C, or more par-

ticularly the chambers X, will operate to instantly and automatically force the valve 15 into closed position whereby it is assured that the valves M will be held in wide open position.

Should it be desired to close the valves M, it is only necessary to move each of the levers 18 inwardly toward the casing C, such movement resulting in a valve M being moved into desired contact with its seat 5 and closing communication between the glass G and boiler and at the same time moving a valve 15 off its seat which allows the steam and water which is trapped within the glass G to be released through the bore of a bushing 11.

Should the glass G become broken while the valves M are open, the pressure which is acting against the valves 15 will be quickly released through such broken glass and the pressure which then rushes from the boiler will force the valves M to their seats, thereby stopping the flow from within the boiler.

From the foregoing description it is thought to be obvious that a valve constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the class described comprising a casing having an offset portion providing a chamber, an extension leading from and in communication with said chamber and provided with an internal valve seat, said extension being adapted for communication with a source of fluid under pressure, a member positioned within the chamber, a link supported for swinging movement by said member, a valve coacting with the internal valve seat of the extension, a wall of the chamber having a port in communication with the atmosphere, a valve coacting with the port, and operative connections between the link and both of the valves to cause said valves to move in unison but in reverse directions, one of said valves being in opened position when the other is in closed position.

2. A device of the class described comprising a casing having an offset portion providing a chamber, an extension leading from and in communication with said chamber and provided with an internal valve seat, said extension being adapted for communication with a source of fluid under

pressure, a member positioned within the chamber, a link supported for swinging movement by said member, a valve coacting with the internal valve seat of the existing, a wall of the chamber having a port in communication with the atmosphere, a valve coacting with the port, operative connections between the link and both of the valves to cause said valves to move in uni-

son but in reverse directions, one of said 10 valves being in opened position when the other is in closed position, and means coacting with the second named valve for manually moving both of the valves.

In testimony whereof I hereunto affix my 15 signature.

CHARLES F. MATTINGLY.
